[57] CLAIM

The ornamental design for a fluorescent lighting fixture,
as shown and described.

DESCRIPTION

FIG. 1 is a front perspective view of a fluorescent lighting fixture showing my new design;
FIG. 2 is front elevational view thereof, the rear being
a mirror image;

FIG. 3 is a left end elevational view thereof;

FIG. 4 is a right end elevational view thereof;

FIG. 5 is a top plan view thereof; and

FIG. 6 is a bottom plan view thereof.

The top of the fixture is shaded to indicate a Mylar-type
surface with a mirror finish.
